CLAIM

The ornamental design for a pocket controller, as shown and described.

DESCRIPTION

FIG. 1 is a front perspective view of my new pocket controller;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The portions of our design shown in broken lines are provided for illustrative purposes only and form no part of the claimed design.
